UNITED STATES PATENT OFFICE.

WILLIAM H. CLISSON, OF BINGHAMTON, NEW YORK, ASSIGNOR TO CLISSON MANUFACTURING COMPANY, INCORPORATED, OF SYRACUSE, NEW YORK, A CORPORATION OF NEW YORK.

GARMENT-PRESSING MACHINE.

Application filed March 6, 1926. Serial No. 92,721.

This invention relates to a garment pressing and ironing machine adapted to be used by tailors, clothiers and the like for steaming, pressing and drying garments which are brought to the machine in a dry condition or may be used for laundering articles which are brought to the machine in a more or less dampened condition.

These operations are usually performed by 10 separate machines which for economical reasons would be prohibitive in the average households and in many public institutions where more or less of both kinds of work are required.

15 The main object, therefore, is to provide a machine capable of functioning for both purposes so that it may be used in households and public institutions where various kinds of drying, cleaning, pressing and light 20 laundry work may be quickly and economically performed.

One of the specific objects is to provide separately movable pressing elements adapted to cooperate with opposite surfaces 25 of a relatively stationary pressing element in such manner that the steaming and pressing of dry garments may be effected between one of the movable elements and corresponding face of the stationary element while 30 damp garments or articles may be simultaneously pressed and ironed between the other movable pressing element and corresponding surface of the stationary element.

Other objects and uses relating to specific 35 parts of the machine will be brought out in the following description.

In the drawings:

Figure 1 is a side elevation, partly in section, of a combined pressing and ironing machine embodying the various features of the 40 invention, both of the movable elements being shown in approximately their pressing positions.

Figure 2 is a longitudinal vertical sectional view taken on line 2—2, Figure 1.

Figure 3 is a transverse vertical sectional view taken in the plane of line 3—3, Figure 2.

Figure 4 is a side elevation of a fragmentary portion of the gear case and adjacent 50 portion of the clutch shifting mechanism as shown more clearly in Figure 3.

As illustrated, this machine comprises a substantially horizontal stationary pressing element —1— and movable pressing elements

—2— and —3— which, in this instance, are 55 arranged respectively above and below the stationary element —1—.

The stationary element —1— is fixedly mounted upon an upright portion —4— of a main supporting frame or standard A and 60 is provided with upper and lower pressing surfaces —5— and —6— for cooperation with the corresponding pressing elements —2— and —3—, the pressing surface —5— being preferably convex in cross section 65 while the surface —6— is concave in cross section to conform to the periphery of the pressing element —3—.

This stationary pressing element —1— is provided with a steam chamber —7— nearly 70 co-extensive with the length and width thereof to which steam is supplied from any available source through a supply pipe —8— for heating both of the surfaces —5— and —6—, said chamber being also provided 75 with a drainage outlet —8— for removing the water of condensation when necessary or desirable.

For convenience of further description, the stationary pressing element —1— may be 80 termed a buck having both of its surfaces —5— and —6— heated when the machine is in operation.

For a similar reason the upper pressing element —2— may be termed the head while 85 the lower pressing element —3— may be termed the feeding roll.

The head —2— is yieldingly mounted upon the front end of a vertically movable rock arm or lever —9— fulcrumed intermediate its ends upon the upper end of a rearwardly and upwardly extending arm —a— of the main supporting frame —A— and having its rear end provided with a counter weight —10—.

The lever —9— is rocked in one direction to force the press head —2— into pressing co-action with the upper surface —5— of the buck —1— by means of a pedal lever —11— and toggle link —12—, said pedal lever being of the bell crank type pivoted at —13— near its angle to the frame —A— near the base thereof.

The forwardly extending arm of the pedal lever —11— is provided with a pedal —11— 105 adapted to be engaged by the foot of the operator for operating the press head to its pressing position against the action of a re-

tracting spring —14— which is connected to the rear end of the lever —9— and to a suitable anchorage —15— on the base of the frame —A—.

5 A pedal operated detent —16— is pivoted at —17— to the base of the frame —A— for engaging a shoulder —18— on the intermediate portion of the front arm of the lever —11— for holding the toggle in its straightened position and thereby holding the press head in its pressing position.

10 The detent —16— is provided with a pedal —19— by which it may be depressed against the action of an expansion spring 15 —20— for tripping the detent from engagement with the lug or shoulder —18— and thereby releasing the toggle and allowing the press head to be opened or swung upwardly and rearwardly under the action 20 of the weight —10— and retracting spring —14—.

25 The rear end of the detent —16— is provided with a lug —21— adapted to engage the underside of the adjacent portion of the lever —11— when the detent is tripped for flexing the toggle at the joint —12— and thus permitting the free action of the spring —14— and counter weight —10— in opening or raising the press head —2—.

30 The forward movement of the upper arm of the lever —11— is limited by a buffer stop —22— on the frame —A— so as to prevent the movement of the toggle joint —12— beyond a straight line between the pivot 35 —13— and the pivotal connection as —9— between the toggle link —12— and lever —9—.

40 The upright bracket —4— is offset laterally mainly to one side of the main upright portion of the frame —A— as shown in Figure 2 while the buck —1— is supported near one end upon the upper portion of the bracket —4— so that the major portion of the length of the buck may extend laterally beyond the bracket to permit the goods to be operated upon to be placed over the free end of the buck practically the entire length thereof without interference with other parts of the machine and also permitting the use of a relatively long feed roller —3—.

45 The bracket —4— is located some distance to the rear of the pressing elements so as to afford ample space or clearance for the articles operated upon by the pressing elements.

50 The press head —2— is practically co-extensive with the length and width of the upper surface of the buck —5— and is also provided with a steam chamber —2'— for receiving steam through a branch supply pipe —23— which is connected to the main supply pipe —24— through the medium of a turning joint —25— co-axial with the axis 55 of movement of the lever —9—.

The bottom of the press head —2— forming the pressing surface may be perforated at —26— to allow the steam to pass therethrough to the surface of the garment during the steaming or pressing operation, the 70 steaming serving to dampen the garment and to render it more pliable and susceptible to shaping under pressure.

75 Any suitable means such as a valve —27— may be provided in the branch pipe —23— for controlling the passage of steam to the chamber —2'—, said valve being adapted to be opened and closed at will by means of a link —28— and handle —29—, the latter being preferably arranged in proximity to the handle as —30— on the front end of the lever —9— for convenience of operation.

80 The feed roller or drum —3— is adapted to cooperate with the lower pressing face —6— of the buck —1— and to rotate about its axis for feeding the articles against the surface —6— for ironing purposes, said feed roll being provided with a peripheral pad —3'— which is more or less resilient and facilitates the picking up and feeding of 90 the articles from the table against the ironing surface without exposing the hands to dangerous contact with the heated iron or feed roll.

95 The feed roll —3— is also movable toward and from the ironing surface —6— of the buck —1— to cooperate therewith for pressing purposes if desired and when released is free to drop by its own weight away from the heated surface to prevent 100 overheating of the padded surface.

105 The feed roller —3— also comprises a tubular or cylindrical member —3''— upon which the pad —3'— is mounted and which is provided with internal transverse partitions —31— and —31'— secured thereto in axially spaced relation and journaled upon an inner sleeve or bushing —32— which is tightly secured at one end in a vertically swinging bracket —4'— on the bracket —4— 110 while its other end extends into the adjacent end of the feed roller for receiving and supporting the partitions —31— and —31'— as shown in Figure 2.

115 A shaft —33— extends entirely through and beyond the opposite ends of the sleeve —32— co-axial with said sleeve and with the feed roller —3— and has its inner end keyed or otherwise secured to the innermost partition —31— for imparting rotary motion 120 to the feed roller.

125 The outer end of the shaft —33— is connected by beveled gears —34— to the upper end of an upright shaft —35— which is also journaled in a suitable bearing in the adjacent portion of the bracket —4— and has its lower end journaled in a bearing in the upper side of an underlying gear case —35'— and provided with a beveled gear —36— within said gear case.

This beveled gear —36— is in constant mesh with a pair of opposed clutch gears —37— which are loosely mounted on a supporting shaft —38— having its opposite ends journaled in corresponding ends of the gear case and its intermediate portion provided with a sliding clutch member —39— splined thereon so as to rotate therewith.

The clutch member —39— is movable from a neutral position shown in Figure 2 to a position in engagement with either one or the other of the gears —37— for reversing the direction of rotation of the feed roller —3—.

15 The means for shifting the clutch member —39— consists of a forked shifting lever —40— pivoted at —41— to the lower side of the gear case —35'— below the shaft —38—, one end of said shifting lever being extended upwardly and laterally through an opening —42— in the adjacent side of the gear case where it is provided with a laterally projecting arm —43— in a plane above the shaft —38—, Figure 3.

25 A sliding bar —44— is mounted in suitable guides —45— to move parallel with and some distance below the feed roller —3— and has its opposite ends provided with downwardly projecting forked arms —46— and —46'—, one of which, as —46—, is adapted to receive the crank pin —43— of the clutch-shifting lever —40— while the other forked arm —46'— is adapted to receive the intermediate portion of a hand lever —47—, Figures 1 and 2.

The rear end of the lever —47— is pivoted at —48— to a cam section —49— to swing about a vertical axis while the cam section —49— is pivoted at —50— to a bracket —51— on the frame —A— some distance below the feed roller —3—, the axis of movement of the cam section —49— being disposed in substantially the same vertical plane as the axis of the feed roller.

45 It is now evident that under certain conditions the lever —47— is free to be moved laterally in either direction about the axis of the pivot —48— and together with the cam section —49— may be rocked vertically about the axis of the cam section which is provided with a raised portion —52— and a depressed portion —53—.

These cam portions —52— and —53— are adapted to engage a roller —54— which is mounted upon an extension —55— of the swinging member —4'— carrying the feed roller —3—, said extension —55— being disposed along the lower side of the feed roller in spaced relation thereto as shown more clearly in Figures 1 and 2.

The roller —54— on the extension —55— is located directly over the cam section —49— and its pivot —50— so that when the cam is rocked about the axis of its pivot by the raising and lowering

of the lever —47— from the dotted position to the full position shown in Figure 1 the high point —52— of the cam section will engage the roller —54— and thereby elevate the feed roller to its pressing position 70 while on the other hand, after the lever —47— is depressed to the dotted position shown in Figure 1, the feed roller will drop by its own weight until limited by the engagement of the roller —54— with the lower 75 point —53— of the cam section.

In order to permit this vertical swinging movement of the bracket —4'— and feed roller carried thereby, said bracket is pivoted at —56— to the bracket —4— of the 80 main supporting frame as shown more clearly in Figure 3 and by dotted lines in Figure 2, said pivots being located as closely as possible to the gear —34— on the shaft —38— so as to prevent disengagement of the 85 gears —34— during the swinging movement of the feed roller to and from the underside of the buck —1—.

The object of this movement of the feed roller away from the underside of the buck 90 is to prevent overheating or burning of the pad of the feed roller when not in use.

Suitable means is provided for preventing the shifting of the clutch from its neutral position and thereby preventing the rotation 95 of the feed roller when the latter is dropped away from the buck and for this purpose the bracket —51— is provided at its front end with a forked extension —58— into which the adjacent portion of the lever —47— is 100 adapted to drop when the lever and cam section are rocked to the position shown by dotted lines to allow the feed roller to fall away from the buck in which case the lever —47— will be held by the opposite arms of 105 the forked extension —58— against lateral movement thereby preventing the shifting of the slide —44— by reason of the fact its forked end —46'— will also be in engagement with the lever —47— as shown in Figure 110 1.

The shaft —38— is preferably driven by an electric motor —59— mounted on the frame —A— of the machine and having its armature shaft provided with a worm 115 —60— meshing with a worm gear —61— on the shaft —38— for imparting rotary motion to said shaft and to the clutch section —39—.

The toggle link —12— is adjustable to 120 effect a corresponding adjustment of the head —2— relatively to the buck —5— particularly when pressing articles of varying thicknesses.

The machine is also provided with a work 125 table —62— and a feeding table —63—, the work table being arranged in a horizontal plane below the feed roller —3— for temporarily supporting the work thereon while the feed table —63— is arranged directly in 130

front of and in a horizontal plane just below the meeting faces of the pressing elements —1— and —3— to facilitate the feeding of the articles by hand to the padded surface of the roller —3— which, by reason of the dampened condition of the articles, causes them to be fed across and against the ironing surface —6—.

- 10 If a garment in a dry state is to be pressed the detent —16— is first tripped to allow the press head —2— to be elevated away from the buck after which the garment may be placed upon the upper surface —5— of the buck and then subjected to pressure by 15 the lowering of the press head during or preceding which the valve —27— may be opened to apply steam to the garment to render the same more pliable for shaping purposes.
- 20 It is evident, however, that other fabric articles may be similarly steamed, pressed and dried between the pressing elements —1— and —2—.

When pressing or ironing previously dampened articles, the lever —47— is raised by hand from the position shown by dotted lines to the position shown by full lines in Figure 1 thereby causing the cam —49— to raise the roller —3— into pressing contact 30 with the ironing surface —6— at which time the intermediate portion of the lever will be brought into registration with the wider upper end of the slot in the forked arm —46'— thus permitting the lateral operation 35 of the lever —47— to throw the clutch section —39— into engagement with one or the other of the clutch gears —37—, Figure 2, thereby effecting the rotation of the roller —3— through the medium of the upright 40 shaft —35— and gears —34—, it being understood that the shifting of the clutch in one direction will cause the forward feeding of the articles across and against the ironing surface —6— while its movement in the 45 opposite direction will reverse the direction of rotation of the feed roller so that by proper manipulation of the lever —47— the article may be fed back and forth across the ironing surface as many times as may be 50 desired.

What I claim is:

1. In a pressing machine of the character described, a pressing element having a pressing surface, a feed roller rotatable in pressing co-action with said surface and having an independent movement toward and from said surface, means including a clutch for rotating the feed roller, means including a hand lever for shifting the clutch, and means actuated by the hand lever for moving the feed roller into pressing co-action with the pressing element.

2. In a pressing machine of the character described, a pressing element having an ironing surface, a feed roller cooperating with

and rotatable relatively to the ironing surface, said feed roller having an independent movement toward and from the ironing surface, means including a clutch for rotating the feed roller, means including a hand lever movable in one direction for shifting the clutch from a neutral position into its engaging position and having an independent movement, and means actuated by the independent movement of the lever for moving the feed roller toward the ironing surface.

3. In a pressing machine of the character described, a pressing element having an ironing surface, a feed roller cooperating with and rotatable relatively to the ironing surface, said feed roller having an independent movement toward and from the ironing surface, means including a clutch for rotating the feed roller, means including a hand lever movable in one direction for shifting the clutch from a neutral position into its engaging position and having an independent movement, means actuated by the independent movement of the lever for moving the feed roller toward the ironing surface, and means for preventing the clutch shifting movement of the lever when the feed roller is moved away from the ironing surface.

4. The combination with a stationary pressing element, having a heated ironing shoe on its underside, a padded feed roller below the ironing shoe for feeding the articles to be ironed thereagainst, means for rotating the feed roller including a drive shaft having its axis intersecting the axis of the feed roller and supporting means for the feed roller movable about the point of intersection of said axes.

5. The combination with a stationary pressing element, having a heated ironing shoe on its underside, a padded feed roller below the ironing shoe for feeding the articles to be ironed thereagainst, means for rotating the feed roller, means for pivotally supporting the feed roller beyond one end thereof to permit it to swing toward and from the ironing shoe, and means for moving the ironing shoe about the axis of its pivotal supporting means.

6. The combination with a stationary pressing element, having a heated ironing shoe on its underside, a padded feed roller below the ironing shoe for feeding the articles to be ironed thereagainst, a shaft operatively connected to the feed roller and extending beyond one end thereof co-axial therewith, a driving shaft having its axis intersecting the axis of the first-named shaft, means for supporting the feed roller to move about the point of intersection of the axes of said shafts, means for transmitting rotary motion from the driving shaft to the first-named shaft for rotating the feed roller,

- and means for moving the feed roller about said point of intersection of the axes of said shafts toward and from the ironing shoe.
7. In a pressing and ironing machine of the character described, a stationary pressing element having an ironing surface on its underside, a feed roller cooperating with said ironing surface, means for pivotally supporting the feed roller at one end and in the axis thereof to swing toward and from the ironing surface, means for moving said feed roller about the axis of its pivotal support and means for rotating the feed roller.
8. In a pressing and ironing machine of the character described, a main supporting frame, a pressing element mounted on said frame and provided with an ironing surface on its underside, a rotary feed roller for feeding the articles against said ironing surface, a support for said feed roller pivoted to the frame beyond one end of the feed roller to permit the feed roller to swing toward and from the ironing surface, said support having an extension underlying the feed roller, means operatively connected to said extension for rocking the support and feed roller carried thereby about the axis of its pivot, and means for rotating the feed roller.
9. In a pressing and ironing machine of the character described, a frame, a pressing element mounted on the frame and provided with an ironing surface on its underside, a bracket pivoted to the frame beyond one end of the ironing surface to swing about a horizontal axis, a feed roller journaled on the bracket to move therewith toward and from the ironing surface, power-driven means including a clutch for rotating the feed roller, means including a hand lever movable in one direction for rocking the bracket upon its pivot to move the feed roller toward and from the ironing surface, said lever having an independent movement in a different direction, and means actuated by said independent movement of the lever for shifting the clutch.
10. In a pressing and ironing machine of the character described, a frame, a pressing element mounted on the frame and provided with an ironing surface on its underside, a bracket pivoted to the frame beyond one end of the ironing surface to swing about a horizontal axis, a feed roller journaled on the bracket to move therewith toward and from the ironing surface, power-driven means including a clutch for rotating the feed roller, means including a hand lever movable in one direction for rocking the bracket upon its pivot to move the feed roller toward and from the ironing surface, said lever having an independent movement, means actuated by said independent movement of the lever for shifting the clutch, and means for preventing said independent movement of the lever when the bracket is adjusted to move the feed roller away from the ironing surface.

In witness whereof I have hereunto set my hand this 13th day of February 1926.

WILLIAM H. CLISSON.
